UNITED STATES PATENT OFFICE.

C. E. AMOS, OF SOUTHWARK, ENGLAND, AND JOHN FRANCIS, OF NEAR BANGOR, NORTH WALES.

MACHINE FOR DRESSING SLATES.

Specification forming part of Letters Patent No. 41,353, dated January 26, 1864.

To all whom it may concern:

Be it known that we, CHARLES EDWARDS AMOS, of the Grove, in the borough of Southwark, and JOHN FRANCIS, of the Penrhynn Slate Quarries, near Bangor, North Wales, in that part of the United Kingdom of Great Britain and Ireland known as England and Wales, have invented Improved Machinery for Dressing Slates; and we do hereby declare that the following is a full and exact description of our said invention.

Our invention of improved machinery for dressing slates relates to a novel arrangement of machinery whereby roofing-slates may be cut, trimmed, or dressed to the different sizes used for building purposes.

The machine consists of a rectangular frame, which may, if necessary, be mounted on wheels for the convenience of transporting or moving the machine from one locality to another. This frame is provided with a fixed knife, and also suitable bearings for a lever or "sword-arm," which carries a movable knife. The sword-arm or lever is suspended by a spring or springs, so that when in a normal position the movable cutting-edge is raised above the lower knife edge, and the two edges resemble a pair of open shears and act in the same manner. A treadle-frame is attached by means of a link to a lever, which is upon the same spindle as the sword-arm, and the knife edges are brought together by the pressure of the foot of the workman; or, if desired, the machine may be worked by mechanical power, by applying power to the treadle-lever, or the treadle-lever may be dispensed with and the power may be applied direct to the sword-arm. The spindle of the sword-arm is made adjustable to compensate for wear in the cutting edge and other working parts, and a gage-plate with suitable marks or points corresponding to the different recognized sizes of roofing-slates is placed on the frame-work, so that the rough slates may be laid in their proper places and adjusted with facility. If desired, a double set of shears or cutting-edges may be employed, so that two sides of the slate may be cut, trimmed, or dressed at the same time, but this will not be found a convenient arrangement in practice.

In the accompanying drawings, Figure 1 is a side elevation of a slate-dressing machine, to

be operated by the foot of the workman. Fig. 2 is a plan view of the same, some of the parts being shown in section. Fig. 3 is an end elevation.

a a a is the frame-work of the machine, which is supported at one end on wheels or rollers *bb*, for the convenience of transporting the machine from place to place. *c* is a fixed cutting-edge, made of steel or other hard metal, and secured to a cast-iron cheek or back plate, which is fixed on the top framing of the machine by screw-bolts and nuts, so that it may be adjusted at pleasure. *d* is a knife or movable steel cutter or shear, secured by bolts or screws to the vibrating sword-arm *d'*, which is mounted at its inner end on a horizontal shaft, *e*. A horizontal lever or arm, *f*, is also mounted on the shaft *e*, and is provided at its other end with an eye, into which is hooked a rod, rope, or chain, whereby the lever or arm *f* is connected with the treadle or foot lever *g* below.

In order to support the sword-arm and movable cutting-edge in an elevated position, as shown at Fig. 1, (so as to be ready to operate upon a slate when it is brought up to the shears,) a coiled spring, *h*, is attached by one end to the arm *d'*, and by the other is suspended from the upper end of a bracket, *i*, which is fixed on the top of the framing. A vertical gage-plate, *j*, is secured in a proper position on the framing by screw-bolts or otherwise, and it must be so adjusted as to be exactly at right angles to the shears.

The operation of the machine is as follows: The workman takes in his hand a slate that requires to be dressed, and having presented one edge to the shears, he places his foot on the treadle *g* and brings down the lever *f* and sword-arm *d'*, and thus cuts and dresses one side of the slate. The dressed side is then placed against the vertical gage-plate *j*, and a fresh undressed side is presented to the shears, which by the workman depressing the treadle *g* are made to trim this side also. The third and fourth sides of the slate are presented to the shears in like manner and are properly trimmed, their edges being cut at right angles to each other and to the proper size, which is done by bringing up the slate to certain marks on the gage-plate *j*. The stationary cutting-edge *c* is adjustable vertically, as shown in Figs. 1 and 2, to compensate for wear; and in

order to adjust the cutting-edge of the upper or movable blade, d , the bearings of the shaft e are made adjustable, as shown in Fig. 3. The ends of this shaft are supported in the blocks k k , which rest on thin pieces of wood, metal, card-board, or other substance, l , and by altering the position or thickness of this packing the shaft e may be raised or lowered bodily, as may be required.

Fig. 4 is a side elevation, and Fig. 5 an end view, of another machine, which is a modification of the one just described. In this instance the treadle is dispensed with, and the movable cutting-shear is operated through the intervention of a cam, m , on the main driving shaft n , which is driven by a band passed around the pulleys o o , and at one end carries a fly-wheel, q . Instead of employing a spring to support the sword-arm d' and keep it elevated when in a quiescent state, as in Figs. 1, 2, and 3, a strong wooden spring or sword, p , is secured in standards r r , above the sword-arm d' , to which it is connected at its outer end by the jointed links s , and the tendency of this spring-sword is to force down the arm d' in the direction of the arrow. The normal or quiescent state of the shears in this arrangement of the cutting-edges is therefore to be closed or shut like a pair of scissors, and in order to open them for the purpose of inserting the rough side of a slate to be trimmed the driving-shaft n must be set in motion, and the cam m , by bearing against and lifting a pin, t , fixed in one side of the sword-arm d' , will raise the same and open the shears so as to admit of a slate being placed between the cutting-edges, but immediately the highest point of the cam passes from under the pin t the arm d' will be forced down by the elasticity and power of the wooden spring-sword p and will cut or trim the edge of the slate. It will

be seen that the axle e of the sword-arm d' is mounted in adjustable blocks k k , as in the former instance, and the bearings of the main or cam shaft n are also adjustable vertically.

It will be seen that the machine shown at Figs. 4 and 5 is not provided with wheels b b , to facilitate its removal from place to place, as the machine when driven by mechanical power is supposed and intended to be stationary, but, if desired, this machine may also be provided with wheels, the same as the smaller machine.

Having now described our invention of improved machinery for dressing slates, and having explained the manner of carrying the same into effect, we claim—

A machine for dressing slates, constructed and operating substantially as herein shown and described.

In witness whereof we, the said CHARLES EDWARDS AMOS and JOHN FRANCIS, have hereunto set our hands and seals, the said CHARLES EDWARDS AMOS this 9th day of October, in the year of our Lord, 1863, and the said JOHN FRANCIS this 5th day of October, in the year of our Lord 1863.
